United States Patent Office

Des. 177,433
Patented Apr. 10, 1956

177,433

CUP

Viktor Schreckengost, Cleveland, Ohio, assignor to The Salem China Company, Salem, Ohio, a corporation of Ohio

Application April 7, 1955, Serial No. 35,398

Term of patent 14 years

(Cl. D44—9)

new design; and

Figure 2 is a bottom view of the cup.

I claim:

The ornamental design for a cup, as shown.
